UNITED STATES = PATENT OFFICE.

JOHN GEORGE HEHR, OF PITTSBURG, PENNSYLVANIA, ASSIGNOR OF TWO-
THIRDS TO EDWARD J. VILSACK AND JOHN J. O'REILLY.

BOTTLE-WASHING MACHINE.

SPECIFICATION forming part of Letters Patent No. 703,415, dated July 1, 1902.

Application filed October 23, 1900. Renewed December 6, 1901. Serial No. 84,945. (No model.)

To all whom it may concern:

Be it known that I, JOHN GEORGE HEHR, a citizen of the United States, residing at Pittsburg, in the county of Allegheny and State of

5 Pennsylvania, have invented or discovered new and useful Improvements in Bottle-Washing Machines, of which the following is a specification.

In the accompanying drawings, which make 10 part of this specification, Figure I is a vertical section on line I I of Fig. II, showing a portion of the bottle-crate and a shot-holder in section. Fig. II is a horizontal cross-section on line II II of Fig. III. Fig. III is a 15 vertical cross-section on line III III of Fig. II, showing the frame in dotted lines.

The object of my invention, generally stated, is to provide means for the economical and expeditious scrubbing, washing, and rinsing 20 of bottles or similar articles.

1 represents a stationary tank having lid 2 and foot-rests 3 3.

4 is a revolving frame having lid 5 and hubs 6 6, said hubs being secured to shaft 7 25 by means of bolts or pins 6' 6', passing through holes in the hubs 6 6 and corresponding holes in the shaft 7.

8 8 are crates resting on lugs 8' 8'.

9 9 are bottles resting in the compartments 30 8' 8' of the cracks 8 8.

10 10 are spring or elastic packers secured to the lid 5 and pressing on the bottoms of bottles 9 9.

11 11 are shot-holders flared outwardly at 35 their mouths 11' 11'.

11' 11' are perforations in the shot-holders, through which the water is permitted to escape. These perforations are smaller than the diameter of the shot 12.

40 11' 11' are sleeve projections acting as guides for the water-exit pipes 13 13.

14 14 are guides for the shot-cut-off valves 15 15, said valves having ports 15' 15'.

16 16 are levers moving in the slots 15' 15' 45 and operating the valves 15 15. These levers are secured to shaft 17. Said shaft has its bearings in the sides of the revolving frame 4.

17' is a lever-handle attached to the ends of shaft 17, by which the valves 15 15 are 50 opened and closed.

18 18 are branch supply-pipes feeding wa-

ter to exit-pipes 13 13 and receiving their source of supply from the hollow portion 7' of shaft 7 by means of flexible tubular connection 19 and pipe 20.

55

21 is a lever-bar pivotally attached to one side of revolving frame 4 by means of bolt 21'.

22 22 are side lever-arms connected to the lever-bar 21 above its axis and secured to crank-arms 23 23 at their outer ends. The 60 crank-arms 23 23 are keyed to shafts 24 24. Keyed also to shafts 24 24 are cranks 25 25. Connected to their outer ends by bolts 25' 25' are hangers 26 26. These hangers 26 26 raise and lower the pipes 18 18 and their 65 connections. Under the pipes 18 18 and secured to the hangers 26 26 are supports 27 27, on which the pipes 18 18 rest.

27' 27' are pins for forcing the pipes down.

The ends of frame 4 are slotted up to the 70 hubs 6 6. This allows one end to be raised and the frame secured in the position indicated by dotted lines in Fig. I by means of a pin inserted through holes 6' of the frame 4 and 6' of the shaft 7.

75

To operate my invention, catches 28 and 29 of lids 2 and 5 are opened, the lids 2 and 5 raised and turned back on their hinges. The crates 8 8, containing bottles 9 9, are lowered onto projections 8' 8', while the head of the 80 bottles 9 9 rest in the mouths 11' 11' of the shot-holders 11 11. The bottles now being in position in the revolving frame 4, lid 5 is closed and fastened by means of latch 29.

The springs 10 10 or other elastic packers 85 press on the bottoms of the bottles 9 9, holding them in position during the operation of scrubbing the interior and dousing their exteriors. Lid 2 is lowered and fastened by means of latch 28. Water is admitted to the 90

hollow portion 7' of the shaft 7. The connection from a base of supply to the hollow shaft 7' can be by any of the well-known means of connecting a stationary inlet-pipe to a revolving exit-pipe 7. The water then passes 95

into the flexible tube connection 19 through pipe 20 into branch connections 18 18 through exit-pipes 13 13 into shot-holders 11 11 and bottles 9 9. The shaft 7 is given a half-turn, which reverses the position of the bottles 9 9. 100

While the bottles remain in the reverse position with their heads up, the shot 12 12 falls

- into them. Power is transmitted through the pulley 30 to shaft 7, turning the frame 4 and carrying the bottles 9 9 around with shaft 7.
- 5 The frame 4 is so mounted on the shaft 7 that it forms an obtuse angle to either the horizontal or vertical plane of the shaft. This obtuse angularity is imparted to the bottles, and while being whirled around with the shaft they are continuously changing their positions, causing the shot to become agitated and to be thrown uninterruptedly throughout the interior, striking the sides and bottoms of the bottles and causing a scouring or 15 scrubbing off of the film of starchy substance and such refuse as is usually found in bottles to be refilled. While the interior portions of the bottles are being scrubbed the exterior portions are repeatedly doused in the 20 water contained in tank 1, preferably below the level of the shaft 7. After the shooting of the bottles is completed lids 2 and 5 are raised. In the meantime shot 12 12 has fallen from the bottles into holders 11. At one end 25 of the frame 4 pin 6' is withdrawn and that end of the frame raised to the position indicated by dotted lines in Fig. 1. The pin 6' is then inserted through hole 6² of the shotted end of frame and into hole 6³ of the shaft. 30 The bottles are now ready to be rinsed. The operator draws the lever-bar 21 toward the opposite end of the frame 4. This movement causes the side lever-arms 22 22 to partly turn shafts 24 24 through their connections, 35 crank-arms 23 23 causing cranks 25 25 to move upwardly, lifting the hangers 26 26. The hangers 26 26 by means of the supports 27 27, attached thereto and under the branch pipes 18 18, raise the said branch pipes 18 18 40 and their connections, while still permitting the water to flow through them by means of the flexible tubular connection 19. The raising of the pipes 18 18 causes the exit-pipes 13 13 to enter the necks of the 45 bottles 9 9. The water passing into the bottles thoroughly rinses their interiors. When the lever-bar 21 is drawn into the position referred to, by which the exit-pipes entered the necks of the bottles 9 9, it also 50 brings into contact with the bottoms of the crates 8 8 lifters 31 31. These lifters are keyed to shafts 24 24 and raise the racks so that the heads of the bottles are out of the mouths of the shot-holders 11 11, which permits the bottles to be more thoroughly rinsed. 55 After the bottles are rinsed the water-supply is cut off, lever-bar 21 reversed to its normal position, racks and bottles removed, pin 6' withdrawn, the end of frame 4 lowered, pin 6' inserted through the hub and shaft, and 60 the machine is ready for its next charge. Means are provided for closing the exit of the shot-holders 11 11 when necessary to repair the machine, so that the shot will not spill out of the holders. I do not, however, 65 limit my invention to the shot-holders being open while the machine is in operation, for assuming the lid 2 raised and the bottles held in position, as shown in Fig. I, and the water passing into the bottles, by making a half-revolution of the shaft 7, bringing the bottle-neck upward, the shot would drop into the bottles. Then by turning lever-handle 17' it 70 would partly turn shaft 17 and cause lever 16 to slide valve 15 15, closing ports 15' 15', keeping the shot and water in the bottles while being shotted, or I could have small openings in that part of the slide-valves which holds the shot in the bottles, while the water could enter the bottles through the openings and 75 still retain the shot in the bottles. 80
- I do not limit my invention to the exact means and method described; but what I desire to claim, broadly, is—
1. In a bottle-washing machine, the combination of a revolving shaft, a frame mounted on said shaft obliquely to the vertical, transverse and longitudinal planes intersecting said shaft, means for securing bottles in said frame, and means for cleaning said bottles. 85
  2. In a bottle-washing machine, the combination of a revolving shaft, a frame attached to said shaft, means for lowering and raising one end of said frame, means for securing bottles in said frame and means for cleaning 90 said bottles.
  3. In a bottle-washing machine, the combination of a tank, a rotating shaft secured in said tank, a frame mounted on said shaft obliquely to the vertical, transverse and longitudinal planes intersecting said shaft, means for securing bottles in said frame and means for cleaning said bottles. 95
  4. In a bottle-washing machine, the combination of a tank, a rotating shaft secured in 105 said tank, a frame mounted on said shaft at an obtuse angle to the line of said shaft, a lid secured to the top of said frame, packers secured to said lid and adapted to press on the bottom of bottles, said bottles resting in 110 racks, said racks secured in said frame and means for cleaning said bottles.

Signed at Pittsburg this 20th day of October, 1900.

JOHN GEORGE HIEHR.
